UNITED STATES PATENT OFFICE.

WILLIAM A. HEIDE, OF DETROIT, MICHIGAN.

CARBURETOR.

Application filed October 1, 1919. Serial No. 327,777.

To all whom it may concern:

Be it known that I, WILLIAM A. HEIDE, a citizen of the United States, residing at Detroit, in the county of Wayne and State 5 of Michigan, have invented a new and useful Carburetor (Case A), of which the following is a specification.

This invention relates to carburetors for utilizing both gasoline and kerosene, it being 10 designed primarily to use the gasoline for priming purposes and for driving the engine until well heated, after which the kerosene can be directed into and mixed by the carburetor.

Another object is to provide a carburetor 15 of this character utilizing a single valve which, when moved in one direction, will admit gasoline to the carburetor in controllable quantities and, when moved in the opposite direction, will admit kerosene in desired amounts.

A still further object is to provide a structure of this character which is compact, durable and efficient and can be controlled 20 readily.

With the foregoing and other objects in view which will appear as the description proceeds, the invention consists of certain novel details of construction and combinations of parts which will be hereinafter more 25 fully described and pointed out in the claim, it being understood that various changes may be made in the construction and arrangement of the parts without departing 30 from the spirit or sacrificing any of the advantages of the invention as set forth in the appended claim.

In the accompanying drawings the preferred form of the invention has been shown.

40 In said drawings—

Figure 1 is a vertical section through a carburetor for use in connection with a vertical intake manifold.

Figure 2 is a horizontal section there- 45 through.

Figure 3 is a vertical section through a modified form of carburetor of smaller capacity and designed for use in connection with a horizontal intake manifold.

50 Figure 4 is a section on line 4—4, Figure 3.

Figure 5 is a detail view of a portion of a modified form of valve.

55 Figure 6 is a similar view of another modified form.

Figure 7 is a perspective view of the

block used in the conduit and which is shown in section in Figure 1.

Figure 8 is a section on line 8—8 Figure 3.

Referring to the figures by characters of reference, 1 and 2 designate separate bowls or receptacles for holding gasoline and kerosene respectively and extending over and secured to each of these bowls is a block 3 each having an angular transversely extending boss 3' extending from the inner side thereof, the blocks being oppositely arranged and the bosses 3' being spaced apart to form therebetween a slot 4. A coupling 70 member 7 is formed at one end of a conduit 8 and provided in opposed walls of the conduit are openings 5 into which the bosses 3' project. The end 10 of the conduit constitutes an air intake. A block 9 is seated 75 against the bottom faces of the bosses 3' and within the conduit 8 and has spaced passages extending therethrough as shown particularly in Figure 9. Side wings 9' extend upwardly from the block 9 and project 80 between the sides of the bosses 3', as shown in Figure 2. For the purpose of holding the blocks 3, conduit 8 and block 9 assembled, screws 6 are extended into the blocks 3 from the outer sides thereof and through 85 the walls of the conduit 8 into engagement with the block 9. See Figure 1.

Formed within the block 3 at one side of the slot 4 are separated pockets 11, 12 and 13 and another pocket 14 is formed in the block at the other side of the slot 4 and directly opposite and in the same plane with the pocket 12. Air ports 15 open into the pockets 11, 12 and 13 and each is intersected by a downwardly extending passage or port 16. Tubes 17 extend downwardly from these passages 16 and into the lower portion of the kerosene bowl 2 while needle valves 18 are mounted in the passages 16 for controlling the flow of fuel and air into the respective pockets 11, 12 and 13 when a suction is set up by the engine through the intake manifold.

An air port 19 opens into the pocket 14 and has a passage 20 extending downwardly therefrom and opening into a tube 21 supported within the gasoline bowl 1. A needle valve 22, horizontally arranged, is provided for controlling the flow of fuel to the pocket 14. A passage 23, communicating through 105 a pipe 23', with a bowl 1, has branch passages 24 for priming fluid, these passages 110

- 24 opening into the slot 4 at points above the pockets and being intersected by a rotary valve 25 adapted to be operated in any suitable manner and normally closed. By 5 providing a series of passages 24 the fuel is delivered in several jets at different points adjacent pocket 14 so that the fuel is thus more thoroughly mixed with the air than would be possible should the same amount 10 of fuel be delivered in a single jet. Floats 26 are mounted in the respective bowls 1 and 2 and are adapted to control the flow of fuel into the bowls from feed pipes, not shown.
- 15 A throttle valve in the form of a flat plate 27 is slidably mounted in the blocks 3 and upon the upper surfaces of the pockets and this plate has separate tongues 28, 29 and 30 which slide within the pockets 11, 12 and 20 13 respectively and are provided with recesses in their free ends. As shown in Figure 2 each recess has its side edges stepped inwardly, as indicated at 31 or if preferred, and as shown respectively in Figures 7 and 25 8 the recesses are V-shaped, as at 32 or rounded as at 33. The free end of the tongue 29 is preferably in transverse alignment with the inner end of the recess in the tongue 30 and the end of the tongue 30 is preferably in transverse alignment with the inner end of the recess in the tongue 28. An opening 34 is formed in the plate 27 directly opposite the tongue 29 and extends 30 throughout the width of the pocket 14. The 25 sides of this opening are stepped as shown and converge toward the free end of the tongue 29. A cut off rib 35 is arranged transversely upon the bottom face of the plate 27, this rib being located between the 40 opening 34 and the end recess in tongue 29.
- When the engine is started it will create a suction through the carburetor. By shifting the plate or throttle valve 27 to the right in Figure 1 the opening 34 will be 45 brought gradually into position within the slot 4 and the rib 35 will be moved into the pocket 12 so as to close communication between passage 15 and slot 4. Thus the suction will draw a portion of the gasoline upwardly from the bowl 1 and through the opening 34 into the intake manifold, said gasoline being mixed with air in the pocket 14 and also in the slot 4. The amount of gasoline supplied to the engine will depend 50 upon the width of the opening 34 exposed in the slot 4. After the engine has been driven for a while with gasoline as a fuel and has become thoroughly heated, the throttle is moved in the opposite direction so as first to bring the inner end of the
- recess in tongue 29 into register with the slot 4. Kerosene will thus be sucked to the engine by way of pocket 12 and the amount of fuel thus supplied will depend upon the position of the tongue relative to the slot 4. 65 After the end recess in tongue 29 has been moved across the slot 4 the end recess in tongue 30 will move to active position and this will be followed by the end recess in tongue 28. Thus the amount of fuel fed 70 to the engine will be gradually increased and, by moving the throttle in the opposite direction, the flow will be gradually cut off. When the throttle is located as in Figure 1 communication between the engine and 75 both bowls 1 and 2 is cut off. To prime the engine it is merely necessary to operate the valve 25 so that gasoline can pass directly from the bowl 1 to the upper portion of the slot 4.
- If the carburetor is to be connected to a horizontal intake manifold the carburetor should be constructed as shown in Figures 3 and 4 wherein the bowls have been indicated at 36 and 37 and 80 the kerosene pockets 38 and 39 are located one above the other. Furthermore the plate forming the throttle valve is arranged vertically, as shown at 40. In this structure the carburetor is shown of less capacity than in 85 the form shown in Figures 1 and 2, there being only two pockets 38 and 39 for the kerosene and, consequently, only two recessed tongues 41 and 42 working in the pockets. In all other respects the structure 90 is substantially like that hereinbefore described, and includes tubes 17' extending from the ports 15 into the bowl 37 and a tube 21' extending into the bowl 36. Valves 18' and 22' control the flow to these tubes 100 17' and 21' respectively.
- What is claimed is:
- In a carburetor the combination with separate fuel bowls and blocks each having a pocket communicating with one of the 105 bowls, of means for admitting air to the pockets, a conduit between the blocks having a slot in its walls, a fuel controlling throttle movable transversely of the slot and within the pockets, there being spaced fuel 110 openings in the throttle either one of which is movable into register with the slot, and a rib carried by the throttle and movable therewith into either of the pockets to close communication between said pocket and the 115 slot.
- In testimony that I claim the foregoing as my own, I have hereto affixed my signature.

WILLIAM A. HEIDE.
